CLAIM

The ornamental design for a valet, as shown and described.

DESCRIPTION

FIG. 1 is a perspective view of a valet showing our new design;

FIG. 2 is a rear elevation view thereof;

FIG. 3 is a front elevation view thereof

FIG. 4 is a left side elevation view thereof, wherein the right side elevation view is a mirror image.

FIG. 5 is a bottom view thereof; and,

FIG. 6 is a top view thereof.

FIGS. 5 and 6 are shown on an enlarged scale.

The broken lines shown in the drawing disclosure are for illustrative purposes only and form no part of the claimed design.

1 Claim, 6 Drawing Sheets
